CLAIM

The ornamental design for a fluid connector, as shown and described.

DESCRIPTION

FIG. 1 is a perspective view of a first embodiment the fluid connector of the present design application; the break lines in the fluid connector body are shown to represent unspecified length

FIG. 2 is a front elevational view of the fluid connector of FIG. 1;

FIG. 3 is a rear elevational view of the fluid connector of FIG. 1;

FIG. 4 is a left side elevational view of the fluid connector of FIG. 1;

FIG. 5 is a right side elevational view of the fluid connector of FIG. 1;

FIG. 6 is a top plan view of the fluid connector of FIG. 1;

FIG. 7 is a bottom plan view of the fluid connector of FIG. 1;

FIG. 8 is a perspective view of the second embodiment of the fluid connector of FIG. 1, with portions shown in broken lines; the break lines are shown to represent unspecified length

FIG. 9 is a front elevational view of the fluid connector of FIG. 8;

FIG. 10 is a rear elevational view of the fluid connector of FIG. 8;

FIG. 11 is a left side elevational view of the fluid connector of FIG. 8;

FIG. 12 is a right side elevational view of the fluid connector of FIG. 8;

FIG. 13 is a top plan view of the fluid connector of FIG. 8; and, FIG. 14 is a bottom plan view of the fluid connector of FIG. 8.

The broken lines in FIGS. 8-14 illustrated portions of the fluid connector that form no part of the claimed design. The design is shown broken away in order to indicate that a specific length of fluid connector also forms no part of the claimed design.
